Garry Sands, Cleveland, Ohio

Application October 6, 1938, Serial No. 233,692

14 Claims. (Cl. 122—250)

This invention relates to heaters, more particularly to hot water heaters, and has for an object the provision of a new and improved heater of this character, and wherein parts thereof are readily assembled or disassembled, as conditions may require, and when assembled the parts are securely fastened together.

Other and further objects of the invention will be apparent to those skilled in the art from the following description of the drawing in which:

Figure 1 is a broken front elevational view, partly in section, of the heater construction,

Figure 2 is an enlarged broken, fragmentary, vertical sectional view, corresponding substantially to the line 2—2 of Figure 1,

Figure 3 is an exploded perspective view of the heater construction, portions of the same being broken away, illustrating the manner in which the parts of the heater may be assembled, while

Figure 4 is a reduced bottom plan view of the heater base.

As shown in the drawing, the invention comprises an elongated outer casing 10, preferably of sheet-metal, and preferably octagonal in cross-section, at the lower end of which there is provided base means 11, carrying an upstanding frame 12, extending along a vertical portion of the casing 10.

The base means 11 preferably are formed from sheet-metal, having an outer curved depending flange 13, substantially octagonal in plan, merging with an upstanding corrugation or embossment 14, at its inner side terminating in a short flange 15, the embossment 14 at its outer side being octagonal in plan, to conform to the shape of the casing 10, the lower edges of the latter being adapted to lie snugly against the outer octagonal surface of the embossment 14 when in position on the base means 11, and to rest upon the flange 13, while the inner surface of the embossment 14, is circular in plan to conform to the contour of a circular inner casing herein-after mentioned.

Seven sides of the octagonally shaped base means are preferably identically formed, but an eighth side 16 is differently formed. The eighth side 16 of the base means 11 is formed to provide a depressed platform 17 the ends of which are defined by elevated, radially extending embossments 18, and the outer limit of which is defined by an elevated connecting embossment 19, the outer walls of the embossments 18 and 19 merging with the adjacent portions of the flange 13, the embossment 14 of course being omitted from the platform area.

The depressed platform 17 is provided for the reception of the lower end of the frame 12, the frame 12 having an angular longitudinally extending flange 20 thereon, shaped to fit within the embossments 18 and 19 and to rest flat upon the platform 17, the flange 20 preferably being spot-welded, or otherwise secured, to the platform 17, to fixedly secure the frame 12 to the base means 11. Both the flange 20 and platform 17 are provided with cut-outs indicated at 21, for a purpose presently to appear, the flange 15, heretofore mentioned defining a circular opening in the base means, which communicates with the cut-outs 21. The frame 12 also comprises at the inner opposite ends of the flange 20, spaced vertically extending sections 22, merging at their upper ends with an arched shaped connecting section 23, one side 24 of the casing 10 being cut out to accommodate the frame 12. The upstanding portions 22, have inclined outer flanges 25 conforming to the contour of the adjacent sides 26 of the casing 10 and overlie the adjacent edges of the cut-out in the casing 10, and the arched section 23 is provided with a vertically extending flange 27 overlying the adjacent part 25 of the side 24 of the casing 10, which defines the casing cut-out, a pair of spaced ears 28 being formed adjacent to the junctions of the upright and arch sections 22 and 23, and through which fasteners, as screws, may be extended to secure the frame to the casing 10. Integrally formed with the vertical sections 22 and with the arched section 23 are inwardly directed webs 29, adjacent the arched section 23 and the upper ends of the vertical sections 22, merging into a vertically extended web 30, having an arcuate opening 31 therein, bounded by an integrally formed inwardly directed semi-circular flange 32, the lower ends of the upright sections 22, being outwardly offset, and merging with the web 30 by offset portions 34, all defining a socket-like depression for the reception of coil securing means herein-after mentioned.

A cylindrical inner casing 35 is disposed within the outer casing 10, and spaced therefrom, the inner casing 35 having a cut-out 36, and an outwardly directed flange 37 surrounding the cut-out, the flange 37 fitting over the outer surface of the web 29 of the frame 12, while the lower edges of the inner casing 35 bear snugly against the inner circular surface of the embossment 14, and rest upon the flange 15, suitable insulating material being arranged between the outer casing 10 and inner casing 35 in a manner well understood in the art.

A top member 38 is provided having a depending flange, octagonal in plan, which fits over the top edges of the casing 10, the top member 38, the base means 11, and the interposed casings 10 and 35 being clamped together by tie rods 40. The top member 38 is provided with an outlet 41 for the products of combustion, and is also provided with an opening through which the threaded end of the water coil 42 is projected, the latter being fastened by a nut 43 to the top member 38, the nut 43 not being intended to support the relatively heavy coil 42, but merely to position the same, the opposite end of the coil 42 being provided with a threaded fitting 44, positioned to extend through the semi-circular opening 31, the fitting 44 having a shoulder 45, adapted to butt against the inner edge of the flange 32, and the threaded portion adapted to receive a nut 46, which lies against the depressed web 30, above the offset portions 34, and when the nut 46 is drawn up, the weight of the coil 42 is supported partially by the frame 12, as will be understood.

The major portion of the weight of the coil, however, is supported by the bottom supporting means 47. The bottom means 47 preferably is circular in outline, dished somewhat to provide a central portion 48, having air vents 49 therein, and a central opening for the passage of a gas pipe 50, carrying a burner 51, inner and outer nuts 52 preferably being employed to clamp the gas pipe in position.

Outwardly of the central portion 48 the bottom means 47 has a horizontally extending flange 52, adapted to be detachably secured to the under surface of the base means 11 by screw bolts 53 taking through suitable apertures therein and adapted to engage suitable threaded bosses in the base means 11, as indicated at 54, the bottom means 47 being of sufficient size to completely close the circular opening in the base means defined by the flange 15, thereby providing for the interception and retention of condensation moisture from the coil 42. It should also be noted that by reason of the upstanding nature of the embossment 14, and the manner in which the casings 10 and 35 are assembled therewith, condensation never enters between the casings, and hence the insulation therebetween is maintained in dry condition at all times.

Rigidly affixed to the flange 52 of the bottom means 47 is an upstanding support 55, preferably corrugated, as at 56, to increase its strength, and at its upper end provided with spaced supporting surfaces 57, arranged generally in semi-circular formation, and of a character to engage the under surface of the shoulder 45 when in position, to provide the principal support for the relatively heavy coil 42, the support 55 being positioned to extend between the side sections 22, and rearwardly thereof, into supporting engagement with the fitting 44 when in operative position.

Once assembled, as described, the relatively heavy coil 42 is supported directly from the base means 11, providing a very strong and attractive construction. If the coil 42 should burn out, or become clogged with foreign matter, the coil may be removed merely by loosening the nut 43, loosening the nut 46, removing the screw bolts 53, and dropping the bottom means 47, and coil 42, from the lower ends of the casings 10 and 35, the support 55 and fitting 44 clearing through the cut-out 21, and the circular opening defined by the flange 15 which communicates therewith, all without disturbing the fixed structural parts

of the heater, and, of course, when the coil 42 has been cleaned, or a substitute provided, the parts may be re-assembled in the manner already described, merely by replacing the same, tightening up the nuts 43 and 46, and replacing the holding screws 53.

It will be apparent to those skilled in the art that I have accomplished at least the principal object of my invention, and it also will be apparent to those skilled in the art that the embodiment herein described may be variously changed and modified, without departing from the spirit of the invention, and that the invention is capable of uses and has advantages not herein specifically described; hence it will be appreciated that the herein disclosed embodiment is illustrative only, and that my invention is not limited thereto.

I claim:

1. A heater construction of the character described, comprising: casing means; base means fixed to said casing means; a heating coil insertible and removable with respect to said casing means through said base means; and supporting means detachably connectable to said base means, and having means for supporting said coil from said base means.

2. A heater construction of the character described, comprising: an outer casing means and an inner casing means spaced apart, and having insulation therebetween; base means fixed to said casing means, and relatively permanently maintaining said casing means and said insulation in position; a heating coil insertible and removable with respect to said casing means through said base means, without disturbing the assembly of said base means, said casing means or said insulation; and supporting means detachably connectable to said base means, and having means for supporting said coil from said base means.

3. A heater construction of the character described, comprising: an outer casing means and an inner casing means spaced apart, and having insulation therebetween; top means, and base means, between which said casing means are relatively permanently clamped; a heating coil insertible and removable with respect to said casing means through said base means, without disturbing the assembly of said top means, said base means, said casing means, or said insulation; and supporting means detachably connectable to said base means, and having means for supporting said coil from said base means.

4. A heater construction of the character described, comprising: elongated casing means; base means fixed to said casing means; a heating coil having a portion adapted to extend laterally through said casing means, insertible and removable with respect to said casing through said base means; and supporting means detachably connectable to said base means, and having means for supporting said coil from said base means; said casing means and said base means being cut out to clear said lateral portion, upon removal or replacement of said coil.

5. A heater construction of the character described, comprising: casing means; base means fixed to said casing means; a heating coil insertible and removable with respect to said casing through said base means; heating means below said coil and within said casing means, said coil having a portion above said heating means adapted to extend laterally through said casing means; and supporting means detachably connectable to said base means, and having means for supporting said coil from said base means; said casing

means and said base means being cut out to clear said lateral portion upon removal or replacement of said coil.

6. A heater construction of the character described, comprising: elongated casing means; base means fixed to said casing means; a heating coil insertible and removable with respect to said casing means through said base means, said coil having a laterally extending portion adapted to extend laterally through said casing means, and adapted for the reception of an exterior holding means; and supporting means, detachably connectable to said base means, and having means for supporting said coil from said base means; said casing means and said base means being cut out to clear the lateral portion of said coil when removed or replaced, the means in which the cut-out of said casing means is formed being depressed inwardly of said casing means to accommodate said exterior holding means.

7. A heater construction of the character described, comprising: elongated outer casing means; elongated inner casing means spaced from said outer casing means, said casing means having insulating material therebetween; base means fixed to said casing means, and having an upstanding embossment against the opposite sides of which said casing means bear; a heating coil insertible and removable with respect to said casing means through said base means, said coil having a laterally extending portion adapted to extend through said casing means, and adapted for the reception of an exterior holding means; and supporting means, detachably connectable to said base means, and having means for supporting said coil from said base means; said casing means and said base means being cut out to clear the lateral portion of said coil when removed or replaced.

8. A heater construction of the character described, comprising: elongated outer casing means, polygonal in cross-section; elongated inner casing means, circular in cross-section, said casing means having insulating material therebetween; base means fixed to said casing means, said base means having an upstanding embossment against the opposite sides of which said casing means bear, the sides of said embossment being contoured to conform to the cross-sectional configuration of said casing means; a heating coil insertible and removable with respect to said casing means through said base means, said coil having a laterally extending portion adapted to extend through said casing means, and adapted for the reception of an exterior holding means; and supporting means detachably connectable to said base means, and having means for supporting said coil from said base means; said casing means and said base means being cut out to clear the lateral portion of said coil when removed or replaced.

9. A heater construction of the character described, comprising: casing means; base means fixed to said casing means; a heating coil insertible and removable with respect to said casing means through said base means, and having a laterally extending portion; and supporting means detachably connectable to said base means, and having laterally offset, upstanding means, engaging the laterally extending portion of said coil for supporting said coil from said base means, said base means having a laterally extending cut-out to permit clearance of said upstanding means when said coil and supporting means are removed or replaced.

10. A heater construction of the character described, comprising: casing means; base means fixed to said casing means; a water heating coil insertible and removable with respect to said casing means through said base means, and having a laterally extending portion; and supporting means detachably connectable to said base means, and having laterally offset upstanding means engaging the laterally extending portion of said coil for supporting said coil from said base means, said base means having a laterally extending cut-out to permit clearance of said upstanding means when said coil and supporting means are removed or replaced; said supporting means spanning the opening in said base means and operable to intercept and retain condensation moisture incident to operation of said heater construction.

11. A heater construction of the character described, comprising: casing means; base means fixed to said casing, a heating coil insertible and removable with respect to said casing through said base means, and having a laterally extending portion; and supporting means detachably connectable to said base means, and having laterally offset upstanding means engaging the laterally extending portion of said coil for supporting said coil from said base means, said base means having a laterally extending cut-out to permit clearance of said upstanding means when said coil and supporting means are removed or replaced; and said supporting means having heating means secured thereto.

12. A heater construction of the character described, comprising: casing means; base means fixed to said casing means; a water heating coil insertible and removable with respect to said casing means through said base means, and having a laterally extending portion; and supporting means detachably connectable to said base means, and having laterally offset upstanding means engaging the laterally extending portion of said coil for supporting said coil from said base means, said base means having a laterally extending cut-out to permit clearance of said upstanding means when said coil and supporting means are removed or replaced; said supporting means closing the opening in said base means and operable to intercept and retain condensation moisture from said coil, and having secured thereto heating means for said coil.

13. A heater construction of the character described, comprising: elongated casing means; base means fixed to said casing means; a heating coil insertible and removable with respect to said casing means through said base means, and having a laterally extending portion adapted to extend laterally through said casing means; and supporting means detachably connectable to said base means, and having laterally offset upstanding means engaging the laterally extending portion of said coil for supporting said coil from said base means, said casing means and said base means having laterally extending cut-out means to permit clearance of said upstanding means and of the laterally extending portion of said coil, when said coil and supporting means are removed or replaced.

14. A heater construction of the character described, comprising: an elongated outer casing means and an elongated inner casing means spaced apart, and having insulation therebetween; base means fixed to said casing means, and relatively permanently maintaining said casing means and said insulation in position; a heat-

- ing coil insertible and removable with respect to said casing means through said base means, without disturbing the assembly of said base means, said casing means or said insulation, said coil having a portion adapted to extend laterally through said casing means; and supporting means detachably connectable to said base means, and having laterally offset upstanding supporting means for engaging the laterally extending por-

tion of said coil for supporting the latter from said base means; said casing means and said base means having laterally extending cut-out means to permit clearance of said upstanding means and of the laterally extending portion of said coil, when said coil and supporting means are removed or replaced. 5
